United States Patent Office.

T. L. VARNS, OF KOKOMO, INDIANA.

Design No. 3,356, dated January 26, 1869.

DESIGN FOR A SLED-RUNNER.

The Schedule referred to in these Letters Patent and making part of the same

To all whom it may concern:

Be it known that I, T. L. VARNs, of Kokomo, in the county of Howard, and State of Indiana, have invented a new and original Design for Bob-Sled Runners; and I do hereby declare that the following is a full, clear, and exact description thereof, which will enable others skilled in the art to make and use the same, reference being had to the accompanying drawings, forming part of this specification.

This invention consists in an improved form or design for a bob-sled runner.

The drawing represents a perspective view of a runner constructed according to my improved design.

I propose to form it by casting it in moulds, so as to form a broad base, *a*, curved in the usual form at the front, having a vertical strengthening-rib, *b*, rising therefrom, and running nearly the whole length of the base, and elevated at the rear, as represented at *c*, for the support of the beam, the said elevation being provided with strengthening-ribs, *d*, and the whole terminating in a plate, *e*, having two vertical sides, *f*,

forming a box for the reception of the end of the beam, wherein the said beam may have ample surface to produce a strong joint, when secured therein by riveting.

Near the front end, the base and strengthening-rib *b* merge in an enlargement, *g*, for the reception of the journals of the tongue-roller, and the end terminating in a flat plate, *h*, projecting backward for the reception of the rabe, to be secured to it by a bolt passing through a hole therein.

Having thus described my invention, I claim as new, and desire to secure by Letters Patent—

The design for sled-runners, herein set forth and shown.

The above specification of my invention signed by me, this 24th day of December, 1868.

T. L. VARNs.
